US0D1000148S

(12) United States Design Patent (10) Patent No.: US D1,000,148 S
Pedersen (45) Date of Patent:  Oct. 3, 2023

(54) SOFA

(71) Applicant: Houe ApS, Ry (DK)

(72) Inventor: Henrik Pedersen, Aarhus C (DK)

() Term: 15 Years

(21) Appl. No.: 35/513,925

(22) Filed: Feb. 25, 2022

(80) Hague Agreement Data

Int. Filing Date: Feb. 25, 2022

Int. Reg. No.: DM/219689

Int. Reg. Date: Feb. 25, 2022

Int. Reg. Pub. Date: Apr. 1, 2022

(51) LOC (14) Cl. 06-01

(52) U.S. Cl. USPC D6/370

(58) Field of Classification Search

USPC D6/369, 370, 371, 372, 373, 374, 375, D6/378, 379
